UNITED STATES PATENT OFFICE

2,032,581

WOOD STAKE SHARPENER

William T. Lane, Tacoma, Wash.

Application June 11, 1934, Serial No. 730,045

4 Claims. (Cl. 144—193)

This invention pertains to devices for sharpening wood stakes to be driven into the ground, such as are used by surveyors, civil engineers, gardeners, tent makers and other persons and for such purposes where wood stakes are required and used. It also pertains to further improvements to my former application, Serial Number 686,054, filed August 21, 1933, and allowed February 24, 1934, Letters Patent No. 1,973,987.

The main object of the invention is to provide a means whereby wood stakes can be sharpened more quickly than with my former invention and with the same perfection. A further object is to provide a means whereby the work can be done by either hand power or by any form of motor power, and thus sharpen wood stakes with greater ease and dispatch.

I attain these and other objects by means of the mechanism illustrated in the accompanying drawings, in which:—

Figure 1 is a front end view of the invention; Fig. 2 is a side view of Fig. 1; Fig. 3 is a top view of the operating mechanism from the line 3—3 of Fig. 2; Fig. 4 is an enlarged top view of the stake sharpening blades; Fig. 5 is a side view of Fig. 4; Fig. 6 is a further enlarged section of the vertical guides of the cutting blades; Fig. 7 is a vertical section of the cutting blades on the line 7—7 in Fig. 4; Fig. 8 is a side elevation of the entire operative mechanism from the lines 8—8 on Figs. 1 and 3; Fig. 9 is a rear end elevation of the invention opposite to Fig. 1; Fig. 10 is an enlarged top view of the stake clamping mechanism; Fig. 11 is a lengthwise vertical section on the line 11—11 of Fig. 10; and Figs. 12, 13 and 14 are enlarged parts of details hereinafter described.

Similar parts are indicated by similar characters in each of the several views.

By referring to the drawings it will be seen that the operative mechanism is supported and operated on a wood structure, though the structure may be of metal parts, if preferred. The structure shown is composed of two horizontal side members 1—1 with a base operating block 2 between. These are shown supported on floor blocks 3—3 at each end, though stout legs of suitable length may be used to support the stake sharpener at a proper height required for operation. A stout upright member 4 rigidly braced by angle irons 5 supports and guides the vertical operation of the invention. The entire structure is approximately thirty inches long, thirty-six inches high and twelve inches wide as shown, though these dimensions may be varied to meet

special uses. The operating or cutting block 2 is made narrow toward the rear with the upper part shaped to a point corresponding to the point to be cut on the stake and to admit the V-shaped cutting blades hereinafter described. This part of the cutting block is capped with a plate of Babbitt metal to protect the wood from being worn in the cutting operation. This plate is identified by the numeral 6.

My former invention was designed to sharpen a wood stake by cutting one side of the stake point at a time. This new improvement is designed to cut two sides of the stake point at one operation.

This is attained by means of a pair of cutting blades 7 adjustably fixed in V-shaped form between two clamping plates 8—8 which are attached to a vertically operating shaft 9. This shaft 9 is attached to and operated by a hand lever arm 10 which is pivotally mounted on a swinging fulcrum 11 supported on a pivot bearing fixed to the upright member 4. This allows the shaft 9 to operate in a true vertical motion through its bracket bearings 12. The clamping plates 8—8 attached to the shaft 9 likewise cause the cutting blades 7 to operate in a true vertical movement by means of adjustable vertical guides 13 and 14—14 placed in triangular form, as shown in Figs. 3 to 6.

The stake to be sharpened is placed on the cutting block 2 between two parallel clamping angle irons 15 and with its point end against a spring actuated vertical stem stop 16. The clamping irons 15 are pressed against the sides of the stake by two pairs of pivoted cams 17, one pair being on the outer side of each iron. These cams are spring actuated by means of a pair of rocking arms 19 and 20 centrally mounted on a shaft 18 across the rear of the invention. Referring to Figs. 8 to 11, it will be seen that the arms 19 and 20 are made at right angles one with the other. The upper horizontal arm 19 extends through vertical slots in an upright fixed guide 21 made rectangular in section. A lift hook 22 made to engage the arm 19 operates within this inclosing guide 21, it being made to operate by the small vertical shaft 23 which is attached to the lever 10 opposite the shaft 9 and is so adjusted as to operate and register in unison therewith. The arm 19 passes through the slots 24 and 25 of the guide 21 and rests on the lower end of the outer slot 25, as indicated in Figs. 8 and 9. This holds the arm 19 in a horizontal position with all parts of the machine at rest with the hook 22 under the arm 19 ready to operate. Referring

to the enlarged Figs. 10 and 11, it will be seen that the lower arm 20 has attached thereto a small drawrod 26 which passes through a rectangular frame 27. Within this frame the drawrod 26 is encircled with a compression spiral spring 28 and a fixed collar 29 which holds the spring in compression against the end of the frame 27 nearest the lever 20. On each outer side of the frame 27 is fixed a push and pull bar 30, each being twisted upward to the under side of the cutting block 2 where they connect with and operate arms 31 which are fixed on the upright shafts 32 of the clamping cams 17.

With this description of the operative parts of the invention, we will consider a wood stake, preferably square and less than three inches in size, as placed on the cutting block 2 with its point end against the spring actuated stop 16. As the lever arm 10 is pressed down, the upward motion of shaft 23 acting in unison with the downward motion of shaft 9, will operate the rocking arms 19 and 20 and draw the pullrod 26 against the spring 28 and thus actuate the bars 30, which will cause the cams to press the clamp-irons 15 against the stake before the cutting blades 7 contact the same. At this point the compression spring 28 yields to the pull and will impart a tighter clutch on the stake till the cut on the two sides is completed. At the finish of the cut 30 the arm 19 has been lifted to the position indicated at 19' where the hook 22 has cleared its hold and the arm 19 being released is spring actuated back to its resting place in the outer slot 25 as at the beginning of the cutting operation. This action is attained by the recoil of the tension springs 33 attached to the lever arms 34 fixed on the outer ends of the shaft 18. This recoil action causes the arm 20 to impart a push action on the bars 30 whereby the cams 17 are actuated to withdraw the clamping irons 15 and release the stake.

The lever arm 10 is now raised to its former position for another downward stroke of the cutting blades 7. The small shaft 23 has pushed the bevel ended hook 22 down within the guiding inclosure 21 until it again engages the lever arm 19, it being actuated into this engagement by the spring indicated at 21'. It will be seen that the shaft 23 is made adjustable by being screw threaded into its lever arm connection as shown in Fig. 12, in order that it will operate the hook 22 in unison with the movement of the cutting blades. The stake is now turned one-fourth over on the cutting block and in position for the other two sides to be cut. The cutting operation as described is again repeated and the sharpening of the stake is completed. The work of sharpening of one stake after another can be thus continued indefinitely, the work being done perfectly and with speed.

60 This invention is not designed to be limited to hand lever operation. By using an operating lever with its longer arm on the rear of the machine, a crank shaft operated by motor power can be attached thereto for operating the machine. A workman can then use all his time in placing the stakes to be sharpened and removing the same when each is sharpened. The work of sharpening the stakes can thus be done with less labor and with greater speed.

70 The stake stop 16 is spring actuated in order that it will not interfere with the downward movement of the clamping device of the cutting blades 7. The encircling compression spring 35 attached to the under side of the cutting block 2 allows it to be pushed down by stud 16' which

contacts the stem 16 as the blades descend. On the lifting of the blades, the stop is at once sprung up to function again as before.

Referring to Figs. 4, 5 and 6, it will be seen that the clamping plates 8—8 are loosely bolted to opposite sides of a central guiding member 36 made to operate in a vertical slot in the metal guide 13. These plates 8 are made to angle outwardly to form the V-shaped angle desired for the sharpening of the stakes and have their front edges engaged to slide in the vertical guides 14. The top edge of each plate 8 is turned squarely inward in a triangular form 37 to provide a means by which they are attached to the vertical operating shaft 9.

15 Each cutting blade 7 is clamped to its respective plate 8 by sub-plate 38 bolted to the inner side of each plate 8. The rear edge of each cutting blade is slightly beveled to fit the angled front edge of the guiding member 36 and each front edge is beveled to fit the beveled edge of each sub-plate 38 as shown at 39. The bevel headed bolt 40 is to be so adjusted that the bevel 39 will tightly clamp the adjoining edge of the cutting blade and securely hold the same in place against each 25 clamping plate 8. Set screws 41 in the top angles of the plates 8 are designed to adjust the cutting plates vertically. The set screws 42 at the rear guide and the set screws 43 and 44 in the front vertical guides are designed to adjust the cutting 30 blades laterally to the sides of the V-shaped cutting block and the Babbitt metal plate fitted thereon.

With the foregoing specification it is believed the construction and operation of the invention 35 will be understood. It is to be observed that the cams are made segmental in form with segmental slots through which studs extend upwardly from the angle irons 15 and serve as a means to withdraw the clamping irons outward and release the 40 stake after the cut is finished.

I am aware that prior to my invention, cutting blades fixed at an angle, one with the other have been used for mitering joints, cutting mouldings and the like, for right angle connections. I do 45 not therefore make any claim on cutting blades as a primary idea, but I do use the blades set in a V-shaped position at an acute angle with each other in the combination mechanism for sharpening wood stakes as herein described.

Having described my invention, I claim:—

1. In a stake sharpening device of the class described, the combination of a supporting structure, an operative lever pivotally mounted on said structure, a cutting element vertically driven by said lever, means cooperating with said driven element to adjust and hold a wood stake in position on a cutting base of said structure to be sharpened by said element, and said means comprising a cam actuated clamping iron on each 60 side of said stake and lever and spring means for operating push and pull bars operatively connected with the said cam actuated clamping irons, whereby the said clamping irons are opened and closed in timed relation with the action of the said 65 cutting element.

2. In a stake sharpening device of the class described, the combination of a supporting structure, of an operative lever pivotally mounted thereon, a vertically guided cutting element 70 driven by said lever, cam actuated clamping irons cooperating with said element to adjust and hold a wood stake to be sharpened by said cutting element, an adjustable shaft attached to the rear end of said operative lever, a hook on the lower 75

end of said shaft, said hook directed and spring actuated within a vertical inclosure to engage a pivoted lever arm extended through said inclosure and a companion arm integral with said pivoted 5 arm and at an angle therewith, and said companion arm having spring and shaft operative push and pull bar connections with the said cam operated clamping irons as described and set forth.

10 3. In a stake sharpening device of the class described, the combination of a supporting structure, an operative lever pivotally mounted on said structure, a vertically guided cutting element driven by said lever, clamping irons cooperating 15 with the said cutting element to adjust and hold a wood stake to be sharpened by said element, cams mounted on shafts to actuate said irons, an adjustable shaft attached to the rear end of said pivotally mounted lever, a hook attached to the 20 lower end of said shaft, means for directing said hook to engage and release one member of a pair of right angled integral shaft mounted lever arms, a pull rod and compression spring attached to

the other member of said pair of arms, said pull rod and compression spring operatively connected with a pair of pull and push bars, and said bars operatively connected with lever arms on the shafts of the cams by which said clamping irons 5 are actuated.

4. In a stake sharpening device of the class described, the combination of a supporting structure; an operative lever pivotally mounted on said structure; a vertically reciprocating cutting element driven by said lever; cam-operated clamps cooperating with said cutting element to adjust and hold a wood stake in position to be sharpened by said cutting element; a pair of integral arms mounted on a pivot shaft; an 15 operative connection between said pivoted lever and one arm of said pair of arms; and tension spring-operated bars connected to the other arm of said pair of arms and operatively connected to the cam-operated clamping irons to release 20 said irons when the downward cut of said reciprocating cutting element is completed.

WILLIAM T. LANE.
